UNITED STATES PATENT OFFICE.

ARNOLD J. PETERSEN, OF CEDAR RAPIDS, IOWA.

DESIGN FOR AN ARM FOR LIGHTING FIXTURES.

60,627.

Specification for Design.

Patented Mar. 14, 1922.

Application filed March 12, 1921. Serial No. 451,884. Term of patent 7 years.

To all whom it may concern:

Be it known that I, ARNOLD J. PETERSEN, a citizen of the United States, residing at Cedar Rapids, in the county of Linn and State of Iowa, have invented a new, original, and ornamental Design for Arms for Lighting Fixtures, of which the following is a specification.

In the accompanying drawing, forming a part of this specification, Fig. 1 is a plan view of an arm for lighting fixtures, showing my new design as seen from the under side, and as attached to a wall-plate indi-

cated in dotted outline. Fig. 2 is an end elevation of the same. Fig. 3 is a side elevation of the same.

I claim:

The ornamental design for an arm for lighting fixtures as shown.

In testimony whereof I affix my signature in presence of two witnesses.

ARNOLD J. PETERSEN.
